UNITED STATES PATENT OFFICE

99,104

DESIGN FOR A LENS GLOBE FOR AN INCANDESCENT ELECTRIC LAMP

Albert L. Arenberg, Highland Park, Ill.

Application July 19, 1935, Serial No. 57,738

Term of patent 14 years

To all whom it may concern:

Be it known that I, Albert L. Arenberg, a citizen of the United States, residing at Highland Park, in the county of Lake and State of Illinois, have invented a new, original, and ornamental Design for a Lens Globe for an Incandescent Electric Lamp, of which the following is a specification, reference being had to the accompanying drawing, forming a part hereof.

In the drawing:

Fig. 1 is a perspective view of the globe, showing my new design;

Fig. 2 is a side view of the globe; and
Fig. 3 is a face view of the globe.

The convex face of the globe is of clear glass, while the side walls are of a character to diffuse the light.

I claim:

The ornamental design for a lens globe for an incandescent electric lamp, substantially as shown and described.

ALBERT L. ARENBERG.
